UNITED STATES PATENT OFFICE

122,676

DESIGN FOR AN IRON RACK

Frank Ascencio, Chicago, Ill.

Application July 2, 1940, Serial No. 93,394

Term of patent 7 years

To all whom it may concern:

Be it known that I, Frank Ascencio, a citizen of the United States, residing at Chicago, in the county of Cook and State of Illinois, have invented a new, original, and ornamental Design for an Iron Rack, of which the following is a specification, reference being had to the accompanying drawing, forming part thereof.

Figure 1 is a top plan view of an iron rack showing my new design.

Figure 2 is a side elevational view thereof, and Figure 3 is a top edge elevational view thereof.

I claim:

The ornamental design for an iron rack, as shown.

FRANK ASCENCIO.
